(No Model.)

F. TRUMP.
WATER WHEEL.

No. 447,850.

Patented Mar. 10, 1891.

UNITED STATES PATENT OFFICE.

FULLER TRUMP, OF SPRINGFIELD, OHIO.

WATER-WHEEL.

SPECIFICATION forming part of Letters Patent No. 447,850, dated March 10, 1891.

Application filed October 29, 1890. Serial No. 369,737. (No model.)

To all whom it may concern:

Be it known that I, FULLER TRUMP, a citizen of the United States, residing at Springfield, in the county of Clark and State of Ohio,

5 have invented certain new and useful Improvements in Water-Wheels, of which the following is a specification, reference being had therein to the accompanying drawings.

This invention relates to certain new and 10 useful improvements in water-wheels.

The invention has for its object to provide a means of supporting the gate-operating ring or annulus in a manner involving a minimum amount of friction; and it consists, essentially, 15 of a ring and of gates having arms whose outer ends compose the arc of a circle struck from the center of the gate-pivots, whereby when the ring is operated to adjust the gates it rolls or travels on the equivalent of numerous anti-friction rollers, as will hereinafter be more fully described.

In the accompanying drawings, forming a part of this specification, and on which like reference - letters indicate corresponding 25 parts, Figure 1 represents a side elevation of a water-wheel embodying my invention, with a part of the casing and ring in section; Fig. 2, an elevational view of the wheel, looking toward the water-entrance side, with a part 30 of the casing and with the ring in section; Fig. 3, a detail perspective view of a gate with one form of arm; and Fig. 4, a similar view of the preferred form.

The water-wheel A, of any approved or well-known type of wheels of this character, is 35 mounted upon a shaft B, having bearings in the discharge pipes or flumes C, and inclosed in a casing D. The flumes are bolted or otherwise secured to the casing, and the casing is preferably constructed in vertical halves and bolted together, as shown. Within the casing and all around the periphery of the wheel are pivotally mounted a number of gates E, which control the admission of water from the 40 casing to the wheel. A convenient manner of so mounting said gates is the provision of an annulus F, secured within the casing at either side, as shown in Fig. 2. The pivot-rod G of the gates has bearings in these annuli. Each 45 gate is provided with an outwardly-extending arm H, the outward end of the arm being fashioned in the arc of a circle whose center

is the center of the pivot of the gate. The dotted circles shown in Fig. 1 suggest that the arms on their outer ends are portions of 55 a circle.

At I in Figs. 1 and 3 it will be seen that the gate-arm is provided with gear-teeth forming the segment of a gear instead of the segment of a wheel or pulley, as in the other example shown in Fig. 1. The ring J for operating the gates is mounted upon these arms, the arms acting as movable supports for the same. If the arms of the gates are toothed, the ring will be correspondingly toothed, as 65 shown in Fig. 1, and if the arms be but segments of a pulley or wheel then some other convenient form of connection between the ring and such arms will be provided. In Fig. 1 I have illustrated a link K pivoted to a lug 70 on the ring and to the arm H of the gate. In either case it will be seen that upon moving the ring in a circular direction the gates will turn on their pivots and be adjusted to open or shut position, while the arms will act as 75 anti-friction rollers for the ring, since they will move with the ring as distinguished from the ring sliding frictionally on them. Thus the ring is supported by the equivalent of so many anti-friction rollers.

A suitable device for operating the ring consists of a rod L, mounted in a stuffing-box, and a lug M on the casing, and connected with a projection O on the ring, and having a thumb-screw P fitted upon its threaded end. 80 In this manner the ring is adjusted back and forth.

In water-wheels having numerous gates which must be held in adjusted positions, and adjusted from one position to another, a ring 90 connected with them must be of considerable weight and must be strongly mounted. When grit and sand get between the ring and its bearings great friction is produced, particularly should said fittings afford, as they usually do, crevices in which the sand can pack. It is to overcome such objection and to reduce the friction, and therefore lessen the labor of manipulating the ring that my invention is designed. It also prevents severe 95 wear and tear on the ring and its fittings incident to friction.

To prevent the ring from becoming dismounted from the gate-arms, it may be

grooved or provided with a circular rim Q to form with the side of the ring a groove in which the arms are placed.

Having thus fully described my invention, 5 what I claim as new, and desire to secure by Letters Patent, is—

1. In a water-wheel, the combination, with a casing and a suitable wheel mounted therein, of a series of pivoted gates having arms 10 whose outer ends constitute the arc of a circle, and an operating-ring mounted upon said arms and connected with said gates, whereby upon moving the ring to adjust the gates the ring rides on the arms as upon anti-friction rollers.

15 2. In a water-wheel, the combination, with a casing proper and a suitable wheel mounted therein, of a series of gates pivotally mounted and having each an arm whose outer end constitutes the arc of a circle, and the operating-

ring mounted upon said arms, and a link connection between said ring and said gates, whereby upon operating the ring to adjust the arms it is moved on the gate-pivots, so that the arms act like anti-friction rollers in 25 their support of the ring.

3. In a water-wheel, the combination, with the casing and a suitable wheel mounted therein, of a series of pivoted gates having arms whose outer ends constitute the arc of 30 a circle, a grooved ring mounted upon said arms, a connection between said ring and each gate, and adjusting devices to manipulate the ring.

In testimony whereof I affix my signature in 35 presence of two witnesses.

FULLER TRUMP.
